BARREL TRANSPORTING DEVICE

Harold S. Houser, Chicago, Ill., assignor to
 Standard Oil Company, Chicago, Ill., a corpora-
 ration of Indiana

Application November 30, 1949, Serial No. 130,133

9 Claims. (Cl. 214—75)

1

This invention relates to an industrial truck of the elevating type, and more particularly relates to trucks adapted for handling a plurality of barrels, rolls of paper, or the like.

To handle groups of upended barrels or the like it has heretofore been necessary to employ pallets or elevated platforms on which the barrels were placed before lifting the group with a fork truck. Such a system is cumbersome and is generally unsatisfactory. Therefore, it is an object of this invention to provide a method and means for handling groups of barrels without employing the pallets. A further object of the invention is to provide an elevating truck in which the elevating member is of a modified form adapted to engage and lift loads comprising upended cylinders such as barrels or rolls of paper in groups or clusters. Another object of the invention is to provide an elevating or lift truck having an improved load engaging means adapted to engage the load at its lower central surface and at its upper peripheral surface.

In general the objects and advantages of my invention are attained by providing a lift truck with an elevating member to which a depending mast is fixed. The lower end of the mast is adapted to be extended laterally and engage the bottom of one or more barrels. An upper barrel restraining frame is movably carried by the elevating member and the depending mast passes slidably through the frame member. Adjustable barrel restraining means are movably carried by the frame and these restraining means are adapted to engage the outer periphery of the top of the load at a point remote from the depending mast which supports the bottom of the load.

These and other features of my invention will become apparent to those skilled in the art to which this invention relates from the following description taken in connection with the accompanying drawings wherein:

Figure 1 is a side view of a truck assembly embodying my invention with the load in an elevated position;

Figure 2 is a top plan view showing the truck and the upper load engaging means;

Figure 3 is a section taken along the lines 3—3 of Figure 1 illustrating the bottom load-engaging elements;

Figure 4 is a fragmentary plan view showing the details of the upper load-engaging means;

Figure 5 is a section along the line 5—5 in Figure 4;

Figure 6 is a fragmentary section along the

2

line 6—6 of Figure 7 of the load engaging means illustrating its retracted and expanded position;

Figure 7 is a section taken along the line 7—7 in Figure 6;

5 Figure 8 is an exploded view showing the individual elements of the lower load engaging mechanism illustrated in Figures 3, 6, and 7;

Figure 9 is a fragmentary elevation showing the action of the load handling elements preliminary to lifting the load; and

10 Figure 10 is a top view along the line 10—10 in Figure 9.

The present invention is particularly adapted for lifting cylindrical containers in groups of 15 3 or 4 and for transporting them without the necessity of employing pallets. By the term cylindrical container I mean to include in addition to drums, barrels and the like, rolls of paper and other generally cylindrical units. As will be understood from the following description, my invention is particularly adapted for the handling of sheet metal drums.

In brief, my invention comprises a hydraulic lift truck including a truck chassis 10 operated 25 on wheels 11 and adapted to be controlled by an operator through control levers 12. At one end of the truck is a vertical guide frame 13 supporting a movable elevating frame 14 which carries the adjustable load engaging mechanism described in considerable detail below.

The elevating frame 14 projects from and is 30 slidably mounted on the guide frame 13 and can be moved vertically thereon by the usual hydraulic elevating mechanism provided on such truck frames and not shown in detail. The adjustable member 15 includes the movable jaws

35 16 to grip the outer periphery of a cluster of barrels 17 and a lower load engaging means including extendable lugs 18 carried by the depending mast 19. The restraining jaws 16 which 40 movably extend through the frame 15 are operated by hydraulic cylinders 21. The mast 19 passes through collar 20 in the restraining frame 15 and enters the space 17a between groups of barrels 17. Then the frame 15 and periphery 45 engaging means 16 are hydraulically lowered toward the cluster of barrels 17. The lugs 18 are extended laterally under the barrels and then the lift member 15 is lowered further onto the top of the barrels and the jaws 16 brought into 50 peripheral contact with the load. The barrel is thereby suspended at three points, i. e. the lug 18 at the bottom and the load engaging jaws 16 at the top. The entire load thus secured can then be raised upon the elevating frame 14.

55

Alternatively, to avoid lateral movement of the load upon extension of the lugs 18, I may first apply some restraining action to the top of the load by operation of the restraining jaws 16.

In the operation of handling barrels with the apparatus described, 3 or 4 barrels of one or more sizes or shapes can be handled whether they be full barrels and half barrels and cylindrical or bulged. In the illustrated embodiment 4 barrels 17 to be transported are arranged in clover-leaf pattern as shown in Figures 2 and 3 and disposed on the plane surface, preferably with the sides of the barrels in contact as shown in Figure 3. However, the peripheral restraining jaws 16 can be used to shift the barrels inwardly so as to assume the described arrangement. If the number of barrels is less than 4 their locations should be those which would result if there were 4 barrels arranged in the described pattern. In other words, the upper periphery engaging jaw 16 and the bottom support means 18 independently assume the load engaging position of Figures 1, 2, and 3 for each barrel whether there be 1, 2, 3, or 4 barrels in the group.

The truck 10 with the elevating frame 14 and restraining member 15 raised to a level above the top of the barrels 17 is moved into position over the cluster of barrels so that the hollow depending post or mast 19 carried by the elevating frame 14 is centered above the opening 17a defined by the group of barrels. The operator then lowers the barrel restraining frame 15 as a unit with the hoisting mechanism of the elevating frame 14 until the lower end of the center post or mast 19 comes to rest on the surface supporting the barrels. Thus the mast 19 is lowered to the floor with the lower lugs 18 in a retracted position as shown in Figure 7. At this point the frame 15 is spaced from the top of the barrels but with jaws 16 extended beyond the periphery of the load as shown in Figure 9.

The lower carrying lugs 18 are extended laterally under the load by the operation of hydraulic cylinder 22 which rotates the center shaft 23 within the tubular mast 19. The barrels 17 are confined by the frame 15 and lateral movement is restrained by the posts or jaws 16 with the result that the knife-edged lugs 18 slide under the chines or lower rim of the barrels 17 until the walls of the barrels seat against the vertical faces 24 of lugs 18. If desired a retractable bumper 28 as shown in Figures 9 and 10 can be provided to tip the barrel 17 outwardly toward jaws 16 and thereby lift the bottom slightly so that the lug 18 can get a purchase on the barrel. The bumper 28 may, for example, comprise an inflatable member mounted on spider 29 which is fixed to the post 19. By deflating bumper 28 the barrel comes to rest on the lug 18. In any event, the jaws 16 are retracted and the restraining frame 15 is then lowered further by the hydraulic cylinder 25 which acts thereon through members 26 (with elevating frame 14 in locked position) until the restraining frame 15 comes to rest on the top of the barrels 17.

The barrel engaging assembly, which includes the frame 15, the upper periphery restraining jaws or posts 16, the center mast 19 and the knife-edged lifting lugs 18, together with their hydraulic operating means, is lifted on the elevating frame 14 as a unit, thereby raising the entire group of barrels. The weight of the barrels is carried on lugs 18 and through the center post or mast 19 to the cantilever arm or elevating

frame 14 which is in turn movably carried by the guide frame 13 on truck chassis 10.

With the barrels so held securely the truck is driven to the new location for the barrels and unloaded on a plane surface by reversal of the operations outlined above. In other words, the lifting frame 15 is lowered on the hoisting mechanism 14 until the center mast 19 and the bottom of the barrels 17 are resting upon the floor. The restraining jaws 16 are moved laterally outward and simultaneously the center shaft 23 within the mast 19 is rotated so as to retract the knife-edged lugs 18. The frame 15 can be raised relative to the elevating frame 14 through the auxiliary supports 26 and the hydraulic lift 25 fixed to the elevating frame 14 which can then be raised so as to withdrawn the center mast 18 before the truck assembly is driven to a new location.

Referring more specifically to Figures 4 and 5, the power of the hydraulic cylinders 21 is independently applied through rod 30 and the linkage 32 to the rack 33, internally threaded pinions 34 and threaded shafts 35 whereby the jaws or posts 16 are moved laterally of the center post or mast 19. The traveling pinions 34 are moved over the threaded portion of the shafts 35 by means of the pivoted linkage 32 traveling in a direction generally transverse to the axis of the threaded shaft 35. A slot 36 is provided in linkage 32 so as to permit continual adjustment about the pin 37 fixed to the operating bar or rack 33. Since the operating bar 33 is anchored to the frame member 15 by elements 38 the rotation of the internally threaded pinions 34 result in the rotation of the shafts 35 and they are moved in a direction transverse to the operating bar or rack 33. The jaws or posts 16 extend through slots 39 in frame 15 and are held down by plate 40 which is fixed to the frame 15.

In Figures 6, 7, and 8 the details of the operating mechanism within the housing 41 at the lower end of the mast 19 are shown. Figures 6 and 7 show the assembled unit and Figure 8 is an exploded view of the elements. A center shaft 23 is provided with a shaft pinion 41 at its lower-most end for engagement with the racks 42 carried by the body 43 of each of the knife-edged lugs 18. The transverse pairs of lugs 18 are in sliding engagement and the pinion gear 41 engages the respective racks 42. Accordingly, when the center shaft 23 is turned by means of the hydraulic piston 22, rack 45, and the upper drive pinion gear 46 fixed to the upper end of the mast 23 as shown in Figures 1, 2, and 4, the lugs 18 are retracted within the housing 41 as shown in Figures 6 and 7. The roller guide 48 keeps the rack 45 in contact with the drive pinion 46. Referring further to Figure 6, it will be noted that in the extended position 48a of the lug 18, the knife-edged faces engage the chine 49 of the bottom of the barrel 17.

The other lugs 18 are also provided with corresponding racks 42 for engagement with another portion of the pinion gear 41 on the lower end of the shaft 23. Accordingly, upon rotation of the center shaft 23 as described above, both pairs of lugs 18 are retracted or extended depending upon the direction of motion of the rack 45 actuated by the hydraulic piston 22.

With further reference to Figures 6, 7, and 8, the housing 41 is fixed to the lower end of hollow mast 19 through which the operating shaft 23 passes. The pinion 41 engages the four racks 42 and controls the position of the lugs 18. The side

bars 50 and 50a are provided with guide channels 51 and 51a within which the lugs 18 are slideable. By this means the movement of the lugs inwardly or outwardly of the housing 47 is in a positive, smooth manner. A bottom plate 46 is held in place by a plurality of machine bolts 52 which pass through bores 53 in side bar 50 and engage the threaded bores 54 in the housing 47.

My invention has been described with reference to the handling of cylindrical objects and in conjunction with a lift truck. It is contemplated, however, that loads comprising crates, packages, or the like as well as barrels or drums can be lifted and transported in accordance with my invention. Likewise, the load engaging means has been described in combination with a vehicle and it is contemplated that this mechanism can be associated with a mono-rail, a crane, or other transporting apparatus. Accordingly, it should be understood that the embodiments of the invention described in more or less detail above and shown in the drawings are for the purpose of illustration only and that many modifications can be made by those skilled in the art without departing from the spirit and scope of the invention herein described or as defined in the appended claims.

I claim:

1. In an apparatus for handling up-ended barrels, the combination of a vehicle, a vertical elevator guide means rigidly carried by said vehicle, an elevating member movably mounted on and projecting from said vertical elevator guide means, an adjustable frame supported by said elevating member and arranged to be moved relative thereto, a plurality of laterally movable barrel-engaging means depending from said frame for engaging the upper periphery of a barrel arranged therebelow, a centrally disposed mast depending from said elevating member, laterally extendable and retractable lugs on the lower end of said mast adapted to engage the bottom of such barrel, and power means for raising and lowering said frame, said power means being connected to said elevating member and adapted to be raised therewith along said elevator guide means.

2. In a lift truck including a vehicle frame, a vertical guide means fixed to the front end of said vehicle frame, and an elevating member mounted to move vertically on said guide, the improvement which comprises an adjustable frame movably mounted on said elevating member and arranged to be positioned over a cluster of up-ended barrels, a plurality of laterally movable jaws carried by said frame and adapted to engage the periphery of the clustered barrels, a mast disposed centrally of said member and slidably through said frame, a plurality of laterally extendable and retractable lug means at the lower end of said mast adapted to engage the bottoms of said barrels, and hydraulically operated means for controlling the positions of said jaws and of said barrel engaging lugs.

3. A lift truck adapted to handle a plurality of up-ended cylindrical objects comprising in combination a vehicle, a vertical elevator guide on said vehicle, an elevating member projecting from said guide and arranged to move vertically thereon, an upper barrel-engaging frame means including retractable restraining jaw means movably mounted on said frame for engaging the upper periphery of said objects, means for raising and lowering said frame relative to said elevating member, a hollow mast depending from said

elevating member and slidably through said frame, retractable lug means carried by the lower end of said mast, a drive shaft extending within said mast and adapted to operate said lug means, a power means for driving said shaft, a second power means for operating said restraining jaw means, and a third power means for raising and lowering said frame means relative to said elevating means.

4. A load handling apparatus comprising an elevating member, a centrally depending hollow mast fixed to said elevating member, a plurality of laterally retractable load-supporting means carried by the lower end of said mast and adapted to engage the lower edge of a load, a drive shaft extending within said central mast, rack means on said load supporting means, a pinion gear on the lower end of said shaft and operatively engaging said rack means, power means engaging the upper end of said shaft for reciprocating said shaft, an adjustable frame means below said elevating member, a pair of laterally extending threaded shafts on said frame means, movable restraining jaw means depending from one end of said threaded shaft through said frame, an internally threaded pinion gear means about each said shaft, a rack means for operating said internally threaded pinion means, mechanical linkage operatively connected to said rack means for rotating said threaded pinions about said threaded shaft, and an hydraulic power means for operating said linkage whereby the said jaw means can be placed in restraining contact with the upper end of the load.

5. A lift truck including in combination a vehicle, a vertical elevator guide means thereon, an elevating member mounted on and projecting from said vertical elevator guide means, movable frame means carried by said elevating member, a depending mast supported by said elevating member, load-engaging means radially extendable and retractable from said mast at the lower end thereof, radially retractable clamping means extending downwardly from the lower side of said frame, and power means for controlling the position of said load-engaging means for raising and lowering said movable frame means relative to said load-engaging means, and for drawing said clamping means radially inward toward said mast.

6. The apparatus of claim 5 including a resilient annular bumper arranged about said mast below said movable frame means whereby the load is tilted outwardly to raise the edge of the load adjacent the load-engaging means.

7. The apparatus of claim 6 wherein the bumper is retractable and comprises an inflatable annular member arranged about the said mast below said movable frame means.

8. A load-handling apparatus comprising an elevating member, a centrally depending hollow mast having its upper end fixed to said elevating member, a plurality of laterally retractable load-supporting means carried by the lower end of said mast and adapted to engage the lower surface of a load, a drive shaft extending within said central mast, a rack and pinion gear means coupling the lower end of said shaft and said load-engaging means, power means engaging the upper end of said shaft above the upper end of said mast for reciprocating said shaft, an adjustable frame means below said elevating member and slidably guided about said mast, a plurality of movable restraining jaw means supported within said adjustable frame means, and

separate power means for individually operating said jaw means whereby said jaw means can be placed in restraining contact with the outer periphery of the upper end of the load.

9. A load-handling device comprising in combination an elevating beam, a hollow depending mast rigidly fixed at its upper end to the elevating beam, an upper restraining frame movably supported by the said beam and centrally guided through a collar in said frame by the said mast, a plurality of separately controlled restraining jaws supported by said frame, and a plurality of extendable and retractable knife-edged lugs carried by the lower end of the said mast and adapted to engage the bottom of a load, whereby the load is clamped between said frame and said lugs and is laterally restrained near the top thereof by said jaws.
